UNITED STATES PATENT OFFICE.

HENRY F. SCHMIDT, OF LANSDOWNE, PENNSYLVANIA, ASSIGNOR TO WESTINGHOUSE ELECTRIC & MANUFACTURING CO., A CORPORATION OF PENNSYLVANIA.

PROPELLER PUMP.

Application filed June 9, 1924, Serial No. 718,906. Renewed June 25, 1926.

This application is a continuation in part of my application, Serial No. 371,648, filed April 6, 1920, and in part of my application, Serial No. 573,050, filed July 5, 1922.

- 5 **5** This invention relates to propeller pumps and it has for an object to produce a pump of this type which is simple in construction and is more efficient than similar pumps now in use and known to me.
- 10 **10** A further object is to produce a propeller pump in which the disk area of the propeller, the spacing of the blades, the axial pitch ratios of the blades, and the areas and proportions of the fluid passages of the pump
- 15 **15** casings are so proportioned and co-related as to produce a pump in which losses, due to shock and cavitation are substantially eliminated.

These and other objects, which will be 20 made more apparent throughout the further description of the invention, are attained by means of a pump embodying the features herein described and illustrated.

25 In the drawings accompanying and forming a part hereof Fig. 1 is a somewhat diagrammatic longitudinal sectional view of a propeller pump embodying my invention. Fig. 2 is a side elevation of a propeller embodying features of my invention and forming 30 a detail of the apparatus illustrated in Fig. 1. Fig. 2^a is an end elevation of the propeller shown in Fig. 2. Figs. 3 to 8, inclusive, are diagrammatic views graphically illustrating principles employed in pumps 35 embodying my invention. Figs. 9, 10 and 11 are illustrative curves or diagrams graphically setting forth features of pumps embodying my invention. Figs. 12 to 15, inclusive, are diagrammatic views explanatory 40 of principles involved in my invention. Fig. 16 is a diagrammatic view showing the effect of the vena contracta co-efficient upon the propeller design.

Throughout the further description of my 45 invention I have employed the word "fluid" in its broad sense, that is, to include both gases and liquids, and the term "pump" is employed in its broad sense, since I do not desire to limit my invention to pump for use in connection with non-compressible fluids.

Referring to the drawings:—

In Figs. 1 and 2, I show more or less di-

agrammatically a practical arrangement of a propeller pump embodying my invention. The pump includes a casing 15 provided with an inlet port 16 and a delivery port 17. As is usual in pumps of this character, the fluid delivery passages converge from the inlet port 16 to a throat at which 20 the propeller is located. This convergence is for the purpose of reducing the velocity of flow at the inlet and incidentally occasions an increase in velocity of flow at the throat such that, under normal operating conditions, the fluid is moving at substantially the axial discharge velocity when acted upon by the propeller. The casing is also shown provided with a divergent outlet which extends from the throat to the port 17. This is also 25 a usual construction and occasions a velocity conversion by which the kinetic or velocity energy of the fluid leaving the propeller is transformed into potential energy in the form of pressure.

75 The propeller 18 is shown mounted on a shaft 19 which extends through a suitable journal formed integrally with the casing 15 and provided at one end with a suitable packing 20. The propeller illustrated is provided with two blades 21 and, as has been said, is located at the throat formed by the converging-diverging fluid passages of the casing. The hub portion 21^a of the propeller is tapered from the inlet to the outlet side 80 of the propeller so as to occasion an additional contraction of the stream lines as the fluid passes through the propeller. In addition to this the tapered hub is employed for the purpose of preventing a phenomenon 85 analogous to that occasioned by obstructing the free flow to all sides of an orifice. This is ordinarily termed a "suppressed orifice" where the flow of one or more sides of the orifice is prevented by the proximity of a 90 wall or diaphragm. In the drawings I have shown a stationary cone or tail piece 22, which, in effect, forms a continuation of the hub portion and is held in place by the directing vanes 23. The tail piece is so proportioned 95 that it forms one wall of the diverging annular passage between the propeller and the outlet port 17. The directing vanes 23 are so designed and so located that they 100 re-direct the fluid issuing from the propeller 105 and deliver it in a direction substantially

parallel to the axis of the propeller. It will be apparent that the vanes are employed primarily for the purpose of converting the rotary velocity of the fluid leaving the propeller into effective velocity along lines parallel to the axis of the propeller. These vanes are so proportioned and disposed that the inlet edges are substantially tangential to the lines of flow leaving the propeller and the fluid is gradually deflected so that the change is accomplished with no shock and a minimum loss occasioned by surface friction.

For the purpose of maintaining substantially uniform flow throughout the inlet passages, I employ directing diaphragms 25 which sub-divide the inlet into at least two sections. These diaphragms are so formed and disposed that they conform closely to the lines of fluid flow, and by dividing the flow, occasion less variation in velocity past points defined by any transverse plane, than would be the case if no diaphragms were employed. The propeller pump shown in the drawings comprises a casing of the elbow type, one leg of which constitutes the entrance leg and the other leg of which is provided with converging and diverging portions and constitutes the pumping leg. The casing is provided with an inwardly-projecting bearing 19' which is in axial alignment with the pumping leg referred to and which supports a drive shaft 19 extending externally of the casing, the propeller 21 being secured to one end of the drive shaft so that it is supported in an overhung manner. The hub portion 21^a of the propeller is arranged adjacent to one end of the bearing 19' and its external surface, in effect, constitutes a continuation of the external surface of said bearing. A fairing cone or tail piece 22 is arranged at the discharge side of the propeller with its base adjacent to the hub portion 21^a so that its external surface in effect constitutes a continuation of the external surface of the hub portion 21^a. The fairing cone or tail piece 22 is supported by directing vanes 23 which serve to correct for the angular discharge of fluid by the propeller, that is, these guide vanes gradually change the direction of flow of the stream from the propeller so that it assumes a direction of flow axially of the diverging portion.

The propeller is so formed that the projected area of the blades is materially less than the annulus area thereof, thereby avoiding the undesirable effects of interfering stream lines in the fluid and resulting eddies at the inlet side of the propeller. The term "projected area" as applied to the blades of the propeller indicates the projected area of the blades upon a plane perpendicular to the axis of rotation of the propeller. The term "annulus or disk area" is used herein to designate the area of the annulus defined by the outer peripheral face of the hub 21^a and the outer tips of the rotating blades 21. The hub 21^a is shown as being tapered; and, in determining the annulus area, the large diameter must be considered as defining the inner circle of the annulus. If the hub should be cylindrical, then the diameter thereof would define such inner circle. The radial pitch of the blades is constant. As the axial pitch of each blade increases from the inlet or leading edge to the outlet or trailing edge, the pitch ratio of the trailing edge is greater than the pitch ratio of the leading edge. This increase of pitch serves to accelerate the fluid as it traverses the propeller to compensate both for the increase in velocity due to the contraction of the stream as it approaches and traverses the propeller and to the discharge of fluid by the propeller at an angle. By the term "pitch ratio" as herein employed is meant the ratio of the pitch of a blade at any point to the diameter of the propeller. For example, assuming a propeller having a 12 inch diameter and a pitch of 9 inches at its leading edge and a pitch of 18 inches at its trailing edge, then the pitch ratio of the leading edge is $\frac{9}{12}$ and of the trailing edge $\frac{18}{12}$.

The ratio of pitch ratios of the trailing edge to the leading edge is, in this illustration, $\frac{18}{12}$ divided by $\frac{9}{12}$, which is equal to 2.

In constructing pumps embodying my invention, I take cognizance of the fact that all particles of a fluid flow along lines of least resistance toward the point of least pressure in the body of the fluid. The convergence of the stream lines set up within a body of fluid by a reduction in pressure at some point within the body is evidenced by the fact that the vena contracta is formed in a jet of fluid issuing from a sharp-edged orifice. In addition, the vena contracta indicates that the fluid approaches the orifice from all possible directions and that the convergence of the stream lines within the body of the fluid continues even after the jet is formed. I, therefore, recognize the fact that the movement of the blades of a propeller through the fluid acted upon occasions a flow through the body of the fluid along stream lines which converge toward the source of the disturbance, or, in other words, extend in a direction parallel to the axis of rotation of the blades of the propeller. I also recognize the fact that the rotary motion of the propeller blades deflects the direction of flow of the fluid, thereby occasioning a flow in a substantially helical path, and that this causes a further contraction of the streams of fluid. I also bear

in mind that the blades are acting upon a fixed column of fluid or, in other words, I recognize the condition occasioned by the fact that the fluid acted upon is confined by the pump casing prior to, during, and after the fluid has been subjected to the direct action to the propeller blades. All these facts are taken into account in the construction and design of pumps embodying my invention, and I have so constructed the pump that a co-relation of the different principles employed in its design is obtained in such a way as to occasion a minimum loss in the transfer of energy from the propeller to the fluid acted upon, and in the conversion of the velocity energy of the fluid to potential or pressure energy.

Referring to the drawings:

Fig. 3 is a diagrammatic illustration of a sharp-edged orifice. The vena contracta of the jet of fluid issuing from the orifice as well as the stream lines which produce this contraction of the jet are illustrated. It is well known that the vena contracta evidences the fact that stream lines are set up in the entire body of the confined fluid and that these stream lines tend to converge toward the center of the orifice.

In Fig. 4, I have diagrammatically illustrated a thin, flat plate submerged in a body of fluid. By considering the flow occasioned under conditions illustrated in Fig. 3, it will be apparent that a transverse movement of the plate 8 in the direction of the arrow will occasion a condition, so far as stream lines are concerned, which is similar to the condition graphically illustrated in Fig. 3. A quick transverse movement of the plate in the direction of the arrow will tend to create a vacuum immediately back of the plate and will occasion a flow of fluid within the body in an attempt to fill or prevent the vacuum created by the movement of the plate. This flow is along stream lines within the body of fluid similar to stream lines formed by the issuance of fluid through the sharp-edged orifice and the conditions of flow will be very similar, since in Fig. 3, the flow is occasioned by a reduction in pressure occasioned by the orifice and in Fig. 4, the flow is occasioned by a reduction in pressure within the body of the liquid occasioned by the transverse movement of the plate. It will be apparent that the entire body of fluid will be more or less affected by the displacement occasioned by the movement of the plate and that the fluid behind and immediately adjacent to the plate will flow at a velocity substantially equal to the velocity of the plate and that the stream lines set up will converge toward the plate, the tendency, of course, being for the liquid to move along lines of least resistance toward the incipient vacuum occasioned by the movement of the plate. It

will, of course, be apparent that cavitation may not actually take place, but the effect of the movement of the plate will be the same within the body of fluid and will differ only in degree if cavitation does actually take place.

Fig. 4, therefore, illustrates that a transverse movement of the plate through a body of fluid will set up converging stream lines throughout the body and that the convergence of these stream lines is toward the origin of the disturbance, in this case, the plate, and that the velocity of the flow in the converging stream lines will increase as the streams converge and that a maximum velocity will be reached at a point immediately adjacent to the moving plate.

In Fig. 5, I have diagrammatically illustrated two plates 8 and 8' submerged in a body of fluid and adapted to be simultaneously moved through the fluid in lines parallel to each other and in directions indicated by the arrows. It will be apparent that the movement of each plate will occasion a disturbance or a local drop in pressure within the body of fluid and will thereby set up lines of flow throughout the body which will conflict with the lines of flow set up by the other plate. While it would be impossible to so space the plates that the flow occasioned by the displacement of one plate would not interfere to some extent with the flow occasioned by the displacement of the other plate, it will be apparent that the spacing of the plates may be such that under certain conditions of displacement, the lines of flow, while interfering, will not interfere to such an extent as to occasion "eddy" currents which will appreciably reduce the efficiency of the plates in their function of creating two well-defined and substantially parallel streams within the body of the liquid. It will be apparent that the plates may be so spaced that under certain conditions of displacement each plate will starve the other. By this I mean each plate may be so spaced that it will prevent the flow of liquid to the point of low pressure occasioned by the movement of the other plate. In Fig. 5, I have graphically illustrated the direction of the lines of flow occasioned by the movement of the two plates 8 and 8' and it will be apparent that a portion of the body of fluid is directly subjected to the influence of both plates, whereas the intensity of this double influence decreases and is almost nil in that portion of the body of the fluid located between adjacent edges of the plates. From the above, it will be apparent that the spacing of the blades of a propeller may be such that their cooperation will set up conflicting streams of lines of flow which will prevent each blade from operating effectively on the liquid or fluid and that on the other hand the spac-

ing may be such that the blades will, in approaching the plate must conform to the direction of the stream lines of the fluid leaving the plate. Under such conditions, the change of direction will be gradual and the stream lines leaving the plate will, in effect, 70 be a continuation of those approaching the plate with the result that gradual change in direction will be accomplished along curved stream lines both in the fluid approaching and in the fluid leaving the plate. In addition, 75 these curved stream lines will converge both by reason of the vena contracta effect illustrated in Figs. 3 and 4, and the change of direction of flow, illustrated in Fig. 6. In order to produce a gradual acceleration 80 of the fluid, without subjecting it to shock, it is necessary that the relative motion of the fluid and the plate should be such that the fluid approaches the working face of the plate along lines which are substantially 85 parallel to the surface of the plate at the entrance or leading edge. It will, however, be apparent that with such a condition of relative motion between the fluid and the plate, the plate would have no propelling 90 effect on the fluid and consequently it is necessary to so arrange the surface of the plate that the angle of the surface with relation to the direction of motion of the plate will increase from the leading to the rear or trailing 95 edge of the plate. It is also necessary that this increasing pitch be so proportioned that the fluid will be gradually accelerated a sufficient amount to compensate for the convergence of the stream lines occasioned by 100 the vena contracta effect and the change in direction of flow.

The fact that the vena contracta of a jet has an area which is less than that of the orifice of its origin indicates that the velocity of flow at the vena contracta is greater for the reason that for the flow of fluids in a conduit, velocity times area is constant. However, where the displacing element moves in a plane substantially at right angles to the axis of the approaching column of fluid, as is illustrated in Fig. 6, the deflection of the stream occasions a still further convergence of the stream lines; and, consequently, the latter convergence occasions an increase in the velocity of flow which is greater than that occasioned by the reduction in area at the vena contracta. 110

The propeller blades of my improved pump must, therefore, have an increasing axial pitch, or such a ratio of pitch ratios of the trailing edges with respect to the leading edges of the blades, so that in acting upon the fluid they will occasion a velocity 115 of flow which is greater than that occasioned by the contraction of the stream as it traverses the propeller and by the change of direction of flow of the fluid discharged from the propeller. Also the ratio of projected blade area to the annulus or disk area 120

It will be apparent that the deflection of the fluid leaving the plate 8^a must be occasioned without shock. This means that 125 the direction of the stream lines of the fluid 130

65

should be such as to secure an undivided and homogeneous discharge so as to completely fill the casing and avoid losses due to eddying or shock. As the area ratio is inversely proportional to the ratio of pitch ratios, the propeller blades are spaced apart sufficiently so that no substantial loss is involved due to stream line interference in the fluid approaching the blades. Experiments indicate that the angular deflection of discharge may vary, for example, from 15 to 30° with respect to the axis of the approaching column.

In Fig. 7, I have illustrated a developed section of a propeller blade in which the section is taken along a cylindrical surface midway between the root and tip of the blade. I have also illustrated diagrammatically the direction of the lines of flow occasioned by moving such a blade through a fluid or liquid in the direction of the arrow associated with the figure. The blade 12, illustrated, increases in axial pitch from the leading to the trailing edge in accordance with the empirical rule above set forth. In Fig. 8, I have shown a similarly developed section of a pump propeller having two such blades and I have diagrammatically illustrated the lines of flow occasioned by such a propeller where the direction of rotation is indicated by the arrow. Lines AA and BB associated with Fig. 8, indicate the common surface of cleavage in developing the section.

In Fig. 8, I show a pump propeller which is provided with two or more blades and it will be apparent that the projected area of the blades should be such as to avoid the effect of flow interference at the inlet side. With respect to the number of blades which the propeller should have, I have experimentally determined that the best efficiency is obtained with the fewest blades and that the efficiency decreases by about 4.5% for each additional blade where the ratio of pitch ratios and the ratio of projected to disk areas remain constant.

In accordance with my invention, the ratio of projected blade to disk areas varies with the contraction co-efficient and the ratio of pitch ratios of the trailing edges with respect to the leading edges of the blades varies inversely with the area ratio. For low discharge pressures or heads, the value of the contraction co-efficient is usually given as 0.625; however, as has been experimentally determined, the contraction co-efficient increases with the discharge pressure or head. Therefore, in designing my propeller pump, first of all, the discharge pressure or head is taken into consideration in correctly determining the projected area ratio and the ratio of pitch ratios.

Assuming, by way of example, that the

contraction co-efficient is 0.625, for low discharge pressure or heads, it will be apparent that the velocity of flow is in the ratio of

$$1 \text{ to } \frac{1}{.625} \quad 70$$

Consequently, for this value of the co-efficient, the angularity or pitch of the displacing surface must be such that its trailing edge will, in acting upon the fluid, occasion a velocity of flow which is greater than

$$1 \text{ to } \frac{1}{.625} \quad 80$$

and in addition be such as to occasion an increase in flow which is greater than the combined acceleration required by the vena contracta and by the change of direction. On the basis of a value of 0.625 for the vena contracta, the above theory indicates that the pitch of the trailing edge should at least be equal to or greater than 1.85 times the pitch of the leading edge. Experiments which I have conducted indicate that the pitch of the trailing edge should actually be about 2 to 2½ times that of the pitch of the leading edge. This discrepancy is probably accounted for by friction and edge losses which are difficult to estimate with theoretical accuracy. The increase in pitch just described is in an axial direction with relation to the propeller, since the radial pitch of the blades is constant.

Figs. 9, 10, and 11 are illustrative of certain experiments which I have conducted. In these experiments, a low head or back pressure was involved and the generally accepted contraction co-efficient of 0.625 was used.

In Fig. 9 for a vena contracta co-efficient of 0.625, the curve shows that the maximum efficiency was attained with blades having a projected area ratio of approximately 60%; however, it is to be understood that the projected area ratio may vary, such ratio being dependent upon the relative area required to secure an undivided and homogeneous discharge which completely fills the pump casing for a ratio of pitch ratios of the trailing edges with respect to the leading edges of the blades necessary to accelerate the fluid traversing the propeller in order to compensate for velocity increases occasioned by the contraction of the stream and by the discharge thereof at an angle.

Fig. 10 indicates the variation in efficiency occasioned by employing pump propellers or having blades of different pitch ratios where the projected area remains constant. The curve indicates that the maximum efficiency was attained when the pitch ratio of the outlet or trailing edge is two and one-half times that of the leading edge.

In Fig. 11, I show the effect on the efficiency of the number of blades, assuming that the pitch and area ratios remain constant. It will be noted that the efficiency decreases with the increase in the number of blades while apparently a maximum efficiency is obtained with a one-bladed propeller. Obviously, however, a one-bladed propeller would ordinarily not be employed because of its inherent unbalance and consequent tendency to vibration.

I desire it to be distinctly understood that the diagrams in Figs. 9, 10, and 11 are merely illustrative in nature and were determined experimentally for a low discharge pressure or head; and, accordingly, I do not desire to be limited to the exact proportioning of parts indicated thereby, as there are many factors entering into the action of propeller pumps and tending by their action and inter-action to slightly shift the salient points of these operating curves in one direction or the other. For example, if the contraction co-efficient is changed, the curves would be changed accordingly.

The requirement that the ratio of projected blade area to disk area, referred to also as the area ratio, shall be sufficient to secure an undivided and homogeneous discharge is obvious from a consideration of Figs. 12, 30 14 and 15. Also, it will be apparent, from Fig. 12, that the ratio of pitch ratios of the trailing with respect to the leading edges of the blades varies inversely as the projected 35 blade area to the annulus or disk area. In Fig. 12, I show diagrammatically and in development, two propeller blades 21 having a smaller ratio of pitch ratios than the pair of blades 30. The blades 21 should have 40 such a ratio of projected to disk area that the fluid discharged therefrom is undivided and homogeneous. Accordingly, the parallel lines indicate the stream lines of flow from the blades 21 and it will be seen that 45 such lines adjoin and that the fluid is not divided by the blades nor is the fluid discharged from one blade intercepted by the other. In like manner, the dash lines from the blades 30 indicate how these blades 50 should be designed in order to secure an undivided and homogeneous discharge.

The importance of having the fluid discharged in an undivided and homogeneous stream is obvious from a consideration of Figs. 14 and 15. In Fig. 14, I show a conduit 31 connected to a larger conduit 32 so as to discharge fluid abruptly thereto. Such a construction is very inefficient as a 55 velocity-pressure conversion device on account of the losses due to eddies, as indicated in the view. Fig. 15 shows how the apparatus shown in Fig. 14 should be modified in order to produce an efficient velocity-pressure conversion device wherein little, if 60 any, eddy losses take place. If the streams 65

of fluid discharged from the propeller blades should not be contiguous so as to constitute an undivided and homogeneous stream, eddy losses would take place for the same reason as in Fig. 14. A consideration of Figs. 14 70 and 15, therefore, shows the importance not only of having the streams of fluid discharged by the propeller blades contiguous and parts of an undivided and homogeneous stream, but also the importance of having 75 the pump casing entirely filled in order to avoid shock and eddy losses.

It is also characteristic of the blades of my propeller that the ratio of pitch ratios varies inversely as the cosine of the angle 80 included between the trailing edge and the plane of rotation. See Fig. 13. In this view, the blade 21, having the smaller ratio of pitch ratios, includes a smaller angle alpha between the trailing edge and the 85 plane of rotation than the angle alpha included between the trailing edge of the blade 30 and the plane of rotation.

As hereinbefore pointed out, my invention comprises a propeller pump in which the ratio of projected blade area to annulus area varies with the contraction co-efficient; and, of course the ratio of pitch ratios varies inversely with the area ratio. I have discussed the general characteristics of my improved pump, as well as the pertinent theory in explanation thereof. I have also considered in detail a pump in which the contraction co-efficient was taken as 0.625. The situation in which a larger co-efficient 90 is involved, due to increased back pressure or head, will now be considered. In a case of this kind, preliminarily to the proper design of a pump made in accordance with my invention, it is necessary, first of all, to determine the back pressure or head and then to determine the ratio of projected blade to annulus or disk area, which varies with the increase in the contraction co-efficient and therefore with the increase in 100 discharge pressure or head. After the area ratio is determined, then in accordance with the rule that the ratio of pitch ratios of the trailing edge with respect to the leading edge varies inversely as the area ratio, the 105 ratio of pitch ratios may be ascertained. If the co-efficient of contraction increases, this means that the propeller blades are called upon to accelerate the fluid less and less to compensate for increase in velocity 110 due to contraction of the stream traversing the propeller.

The effect of increasing back pressures or head is illustrated by diagrammatic Fig. 16. From this view, it will be seen that, for an 115 increase in pressure or head, the co-efficient of contraction, indicated by the curved line designated "co-efficient of contraction", increases and that the area ratio varies with 120 the contraction co-efficient, and that the 125 130

ratio of pitch ratios (indicated by the curve so designated) varies inversely with the contraction co-efficient.

The advantages in improved efficiency attained in the employment of the pump of this invention arise from the absence of eddying currents in the stream passing to, through and from the propeller, and from the union without shock of the separate columns of fluid projected or delivered by the separate blades of the propeller to form a homogeneous stream outwardly flowing from the propeller. The essential relations in the propeller construction of axial pitch and projected area to the contractual co-efficient of the stream traversing the propeller, as hereinabove fully described and set forth in the appended claims, result in the attainment of the above indicated improved operative characteristics of the propeller pump of the present invention.

While I have shown my invention in but one form, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. In combination in a propeller pump or fan, a propeller comprising a hub portion, blades mounted thereon and having a projected area of approximately 60% the disk area, and an axial pitch at the outlet edge, so proportioned with relation to the pitch at the inlet edge as to compensate for the increase in velocity due to the contraction of the stream lines in the fluid traversing the propeller and the contraction due to the angularity of the stream lines leaving the blades.

2. In combination in a fluid impeller of the propeller type, a propeller comprising a hub portion, blades mounted thereon and having a projected area of approximately 60% the disk area, and an increasing axial pitch, the pitch ratio of the leading edge of each blade being such as to receive the fluid without shock and increasing to a pitch ratio at the trailing edge such as to occasion an increase in velocity greater than that occasioned by the contraction of the stream lines as the fluid traverses the propeller and the contraction occasioned by the angularity of the stream lines leaving the blades of the propeller.

3. In combination in a pump, a propeller, comprising a hub portion, blades mounted thereon, having a projected area materially less than the disk area, and having an increasing axial pitch, the ratio of the pitch

having an inverse relationship to the ratio of the projected area to the annulus or disk area.

4. In combination in a pump, a propeller, comprising a hub portion, blades mounted thereon, having a projected area materially less than the disk area, and having an increasing axial pitch, the ratio of the pitch ratios from the trailing to the leading edge being greater than the ratio of the disk area to the projected area. 75

5. In combination in a pump, a propeller comprising blades having increasing pitch from the leading to the trailing edge, the increase of pitch having a definite relation to 80 the projected area ratio.

6. In combination in a pump, a propeller comprising blades having increasing pitch from the inlet to the outlet edge, the increase in pitch being inversely proportional to the 85 projected area ratio of the blades and also inversely proportional to the cosine of the angle which the trailing edge of the blade makes with the plane of rotation.

7. In combination in a propeller pump, a propeller having a projected area materially less than the disk area and an increasing pitch from the leading to the trailing edge, the ratio of the pitch ratios being such as to 90 compensate for the increase in velocity occasioned by the contraction of the stream lines of the fluid traversing the propeller and the contraction of the stream lines occasioned by the angularity of the stream lines leaving the propeller. 95

8. In combination in a pump, a casing having working passages formed therein and a propeller mounted within said casing and having a projected area materially less than the disk area and increasing axial pitch such 105 that the separate streams projected by the separate blades of the propeller unite to just fill the delivery passage of the pump without shock or cavitation.

9. In combination in a propeller pump, a 110 casing having working passages formed therein, and a propeller located within the working passages of the pump and having a projected area of approximately half the disk area, and an increasing pitch such that 115 the separate streams projected by the separate blades of the propeller unite to just fill the delivery passage of the pump without shock or cavitation.

10. In combination in a propeller pump, a 120 casing having a converging-diverging working passage, and a propeller located at the throat of said passage, and having a projected area of approximately 55% of the disk area of the propeller and an increasing 125 pitch from the leading to the trailing edge of each propeller blade.

11. In combination in a propeller pump, a casing having a converging-diverging working passage, and a two-blade propeller lo-

- cated at the throat of said passage and having a projected area of approximately half of the disk area of the propeller, and an increasing pitch from the leading to the trailing edge of each blade.
12. In combination in a propeller pump, a casing having a converging-diverging fluid passage, a two-bladed propeller located at the throat of said passage and having a projected area substantially less than the disk area and an increasing axial pitch whereby the separate streams of fluid projected by each blade unite to form a single stream substantially filling the outlet portion of said passage and homogeneous throughout as regards continuity of flow.
13. In combination in a propeller pump, a casing having a converging-diverging fluid passage, a two-bladed propeller, located at the throat of said passage, and having a projected area of substantially half the disk area.
14. In combination in a propeller pump, a casing having a converging-diverging fluid passage, a two-bladed propeller, located at the throat of said passage, and having a projected area of approximately half the disk area, and having an increasing axial pitch.
15. In combination in a propeller pump, a casing, a two-bladed propeller located within the casing and having a projected area materially less than the disk area, and an increasing axial pitch such that the axial pitch at the trailing edge of each blade is substantially twice that at the leading edge.
16. In combination in a propeller pump, a casing, a two-bladed propeller mounted therein of constant radial pitch and having a projected area of approximately one half the disk area and an increasing axial pitch.
17. In combination in a propeller pump, a casing having a converging-diverging fluid passage, a two-bladed propeller mounted therein at the throat of said passage and of increasing axial pitch, the ratio of the pitch ratios from the leading to the trailing edge being substantially inversely proportional to the ratio of the projected area to the disk area.
18. In combination in a propeller pump, a casing having a converging-diverging fluid passage, and a propeller mounted at the throat of said passage and having blades, the projected area of the blades being materially less than the annulus or disk area, the radial pitch of the blades being constant, and the axial pitch of the blades increasing from the leading to the trailing edges.
19. In combination in a propeller pump, a casing having a converging-diverging fluid passage, and a propeller mounted at the throat of said passage and having blades, said blades having a projected area approximately one half the disk area, a constant radial pitch and an axial pitch increasing from the leading to the trailing edges.
20. In combination in a propeller pump, a casing having a converging-diverging fluid passage, a propeller located therein at the throat of said passage and having a constant radial pitch and a projected area materially less than the disk area.
21. In combination in a propeller pump, a casing having a converging-diverging fluid passage, a two-bladed propeller located therein at the throat of said passage, having a constant radial and an increasing axial pitch, and a projected area of approximately half the disk area.
22. In combination in a propeller pump, a casing and a propeller arranged therein, the axial blade pitch of the propeller increasing from the leading to the trailing edges, the ratio of the pitch at the trailing edge to the pitch at the leading edge being approximately an inverse function of the pressure head at the discharge side of the propeller.
23. In a propeller pump, a propeller having blades which increase in axial pitch from the leading to the trailing edges, the ratio of the pitch at the trailing edge of the blade to the pitch at the leading edge thereof being approximately an inverse function of the contraction co-efficient of the stream traversing the propeller.
24. In a propeller pump, a propeller having blades which increase in axial pitch from the leading to the trailing edges, the rate of increase in the blade pitch being approximately an inverse function of the pressure head at the discharge side of the propeller.
25. In a propeller pump, a propeller having blades which increase in axial pitch from the leading to the trailing edges, the rate of increase in the pitch of the blade being approximately an inverse function of the contraction co-efficient of the stream traversing the propeller.
26. In a propeller pump, a propeller having blades whose ratio of projected blade area to annulus or disc area is proportional to a function of the contraction of the stream traversing the propeller and whose ratio of pitch ratios of the trailing edges of the blades with respect to the leading edges is approximately proportional to an inverse function of the area ratio.
27. In a propeller pump, a propeller having blades whose ratio of projected blade area to annulus or disc area is proportional to the extent of contraction of the stream traversing the propeller and whose ratio of pitch ratios of the trailing with respect to the leading edges is approximately inversely proportional to the area ratio.
28. In a fluid impelling device, a plurality of similar blades mounted for movement in

the same path, the projected area of said blades on the surface swept over by the discharge edges of said blades being between 50% and 62.5% of the area of said surface.

29. In a fluid impelling device, a plurality of similar blades mounted for movement in the same path, the projected area of said blades on the surface swept over by the discharge edges of said blades being

between 50% and 62.5% of the area of said surface, said blades having an increasing pitch from the leading to the trailing edges thereof, the ratio of the pitch ratios of the leading to the trailing edge having a converse relationship to said area ratio. 15

In testimony whereof, I have hereunto subscribed my name this 23rd day of May, 1924.

HENRY F. SCHMIDT.

the same path, the projected area of said blades on the surface swept over by the discharge edges of said blades being between 50% and 62.5% of the area of said surface.

29. In a fluid impelling device, a plurality of similar blades mounted for movement in the same path, the projected area of said blades on the surface swept over by the discharge edges of said blades being

between 50% and 62.5% of the area of said surface, said blades having an increasing pitch from the leading to the trailing edges thereof, the ratio of the pitch ratios of the leading to the trailing edge having a converse relationship to said area ratio. 15

In testimony whereof, I have hereunto subscribed my name this 23rd day of May, 1924.

HENRY F. SCHMIDT.

Certificate of Correction.

It is hereby certified that in Letters Patent No. 1,596,459, granted August 17, 1926, to Henry F. Schmidt, of Lansdowne, Pennsylvania, for an improvement in "Propeller Pumps," an error appears in the printed specification requiring correction as follows: Page 8, line 124, claim 27, after the word "trailing" insert the words *edges of the blades*; and that the said Letters Patent should be read with this correction therein that the same may conform to the record of the case in the Patent Office.

Signed and sealed this 2d day of November, A. D. 1926.

[SEAL.]

WM. A. KINNAN,
Acting Commissioner of Patents.
